Hartford, Conn., as trustee

Application December 11, 1951, Serial No. 261,107

Claims priority, application Netherlands
January 12, 1951

5 Claims. (Cl. 219—47)

1

The invention relates to high-frequency furnaces which are provided with an output tube having an oscillatory circuit included in the anode circuit and has for its object to provide an improved structural embodiment of such an apparatus.

In order to obtain a favorable output, i. e. to ensure maximum power in the load circuit and in order to avoid overload and/or excess voltages, it is common practice, particularly in high-frequency furnaces of high power, to use means to adapt the load resistance to the output tube. For this purpose the load circuit and the anode circuit of the output tube may be coupled through an autotransformer provided with taps or through a variometer formed by the circuit coil and a coupling coil included in the load circuit.

The structural improvement provided by this invention is of particular importance for high-frequency furnaces of high power, for example, of 1 kw. or more, in which the circuit coil of the said oscillatory circuit may be force-cooled by air or water.

According to the invention, in a high-frequency furnace of the said type the circuit coil and the associated circuit capacitor(s) are relatively rigidly fixed and form a structural unit, which is adapted to be displaced as a unit in the high-frequency furnace and hence relatively to the coupling coil of the load circuit, which is rigidly secured therein.

In order that the invention may be more clearly understood and readily carried into effect, it will now be described more fully with reference to the accompanying drawing, in which:

Fig. 1 shows a schematic diagram of a high-frequency furnace according to the invention; and

Fig. 2 shows in a perspective view the construction according to the invention.

In the circuit-arrangement shown in Fig. 1 the high-frequency energy required for heating is taken from an electron tube oscillator including a triode 1. The anode circuit of the tube oscillator, which is constructed in the form of a Colpitt circuit, includes a circuit 2, which determines the oscillator frequency, and which contains a circuit coil 3, shunted by two series-connected circuit capacitors 4 and 4'. One end of the anode circuit 2 is connected through a blocking capacitor 5 to this anode, the other end is connected through a grid capacitor 6 to the control grid of the tube 1. A leak resistor 7 is connected in series with a choke 8 to the grounded cathode of the tube 1.

2

The junction of the capacitors 4 and 4' is also grounded. The supply voltage for the anode of the tube 1 is derived through a choke 9 from a direct voltage source 10.

5 The circuit current produced across the oscillatory circuit 2 during the oscillation is used for heating a workpiece included in a load circuit, formed, for example, by a heating coil 13; for this purpose the circuit 2 is inductively coupled with a coupling coil 11, to the output terminal 12 to which the heating coil 13 is connected.

According to the invention, in order to adapt the load to the generator when the operational conditions vary, the circuit coil 3 and the associated circuit capacitors 4 and 4' are arranged to be stationary relative to one another and form one structural unit 15, which may be displaced as a unit in the high-frequency furnace and hence may be displaced relative to the coupling coil 11 of the load circuit, coil 13 being held stationary within the furnace. The load supply leads 16, 17 and 18 of this structural unit 15 and the tube are flexible.

20 The structural embodiment is shown in a perspective view in Fig. 2; corresponding elements of the two figures are designated by the same reference numerals.

The tuning circuit includes a circuit coil 3, the turns of which are formed by hollow copper pipes, in order to permit water cooling of the coil. The inlet and outlet ducts for cooling of the circuit coil are shown at 19 and 20. The cooling ducts 19 and 20 are made of insulating material, for example, rubber or plastic. The ends of the circuit coil 3 are connected to mica capacitors 4 and 4' of the stacked type, which are preferably housed in a closed screening box 31 (shown in broken lines). The circuit coil 3 and the capacitors 4 and 4' are secured to a carrier plate 22, which is provided with wheels 23, only one of which is shown in the drawing. The structural unit thus formed 3, 4, 4', 19, 20, 21 and 22 is slidable along rails 24 in the axial direction of the coil 3, for example, through use of a chain drive, or else a toothed gear and rack transmission, in a manner such that the displacement can be carried out from the control-panel of the high-frequency furnace. The circuit coil 3 is constructed in the form of a cylinder winding and adapted to be displaced in an axial direction by the displacement of the structural unit relative to the coupling coil 11, which surrounds the circuit coil and is made of cylindrically bent broad copper ribbon and arranged so as to be insulated. The coupling coil 11 is provided with terminals 12, to which the

further load circuit is connected. One of the terminals 12 of the coupling coil is normally grounded, but, as an alternative the ground point of the coupling coil 11 may be shifted in place by 180° or 90° with respect to the output terminals 12.

The unit is preferably made so as to be displaceable through a distance equal to the length of the circuit coil 3, the length of the coupling coil being adapted to this length. In a high-frequency furnace an adaptation of load may thus be ensured in a range which is sufficiently great for all practical uses. The ends of the circuit 2, which is constructed as a unit, are secured through flexible connecting leads 17 and 18 to the further stationary part of the oscillator circuit. The connecting lead 13 is coupled through a blocking capacitor 5 with the anode of the tube 1 and the connecting lead 17 is coupled through a grid capacitor 6 with the control-grid of the tube 1 and through a coil 8 with a grounded leak resistor 7. The junction of the circuit capacitors 4 and 4' is connected as shown in Fig. 2, through a lead 16' to the ground plate 22 and is grounded by way of the wheels 23 and the grounded rails 24.

The tube 1 is arranged laterally with respect to the displaceable structural unit, thus providing the further advantage that the loops of the flexible connections are only slightly deformed, when the structural unit is displaced. A screening strip 27 (partly removed in the drawing) is inserted between the tube and the circuit unit in order to avoid unwanted coupling of the grid circuit of the tube with other circuit elements. Any tendency of the circuit-arrangement towards parasitic oscillation is thus strongly reduced. For the same reasons it is desirable to provide a screening plate 28 between the grid circuit and the anode circuit of the tube.

In the practical construction of the high-frequency furnace described above use was made of copper screening plates at right angles to the field of the coils and arranged on either side of the coupling coil 11 and the circuit coil 3; one plate (25) is shown in broken lines in the figure, the other (26) forms part of the screening box 21. These screening plates are provided in order to permit housing the high-frequency furnace in a sheet-iron cabinet without electrical interference.

In the high-frequency furnace according to the invention, the flexible connections 16 to 18 do not transmit the comparatively high circuit or load currents, in contradistinction to known constructions of high-frequency furnaces. In the practical construction of a 10 kw. high-frequency furnace comprising two tubes TBW 6/6000 in parallel connection, operating as the output tube, the flexible connections transmit approximately 3 amp. with a circuit current of about 80 amp.

The use of the invention provides a construction of a high-frequency furnace, which is attractive from the electrical point of view, the ad-

vantages of this construction largely compensating for the slightly less simple structural arrangement, particularly with the use of high-frequency furnaces of high power.

5. What I claim is:

1. A high-frequency furnace including an output discharge tube having an output electrode and an oscillatory circuit coupled to said electrode and constituted by a coil and a capacitance, a carrier for supporting said coil and said capacitance as a structural unit, an output coil fixedly mounted in said furnace for inductively coupling said oscillatory circuit to a load, and means movably mounting said unit in said furnace to effect displacement of said circuit coil relative to said coupling coil.

2. A furnace as set forth in claim 1 further including means to force-cool said circuit coil.

3. A high-frequency furnace including an output discharge tube having an output electrode and an oscillatory circuit coupled to said electrode and constituted by a coil and a capacitance, said circuit coil being wound in the form of a cylinder, a carrier for supporting said coil and said capacitance as a structural unit, an output coil fixedly mounted in said furnace for inductively coupling said oscillatory circuit to a load, said output coil being constituted by a cylindrically bent ribbon and surrounding said circuit coil, and means movably mounting said unit in said furnace to effect axial displacement of said circuit coil relative to said coupling coil.

4. A furnace as set forth in claim 3 wherein said tube is laterally displaced from said structural unit.

5. A high-frequency furnace including an output discharge tube having an output electrode and an oscillatory circuit coupled to said electrode and constituted by a coil and a capacitance, said circuit coil being wound in the form of a cylinder, a rolling carrier for supporting said coil and said capacitance as a structural unit, an output coil fixedly mounted in said furnace for inductively coupling said oscillatory circuit to a load, said output coil being constituted by a cylindrically bent ribbon and surrounding said circuit coil, and means including rails for moving said rolling carrier in said furnace to effect axial displacement of said circuit coil relative to said coupling coil through a distance equal to the axial length of said circuit coil.

LOURENS BLOK.
